UNITED STATES PATENT OFFICE

121,898

DESIGN FOR A VISE STAND

Carl H. Ingwer, Elyria, Ohio

Application December 29, 1939, Serial No. 89,214

Term of patent 14 years

To all whom it may concern:

Be it known that I, Carl H. Ingwer, a citizen of the United States, residing in Elyria, in the county of Lorain and the State of Ohio, have invented a new, original, and ornamental Design for a Vise Stand, of which the following is a specification, reference being had to the accompanying drawing, forming a part thereof.

Fig. 1 is a perspective view of a vise stand illustrating the design of my invention;

Fig. 2 is a perspective view from the opposite end.

I claim:

The ornamental design for a vise stand, as shown.

CARL H. INGWER.
